UNITED STATES PATENT OFFICE

THOMAS C. GRACE, OF MANOR, PENNSYLVANIA

HOSE-SUPPORTER CLASP

Application filed October 6, 1928. Serial No. 310,807.

My invention relates to certain new and useful improvements in hose supporter clasps, and while primarily intended for ladies' hose supporters, it will be obvious that the device may be employed for any other purposes wherein it is found to be applicable.

Important objects of the invention are to provide a supporter clasp of the character described, which will engage a stocking without liability of causing runners and tears therein or otherwise impairing same, which embodies a resilient member affording permanent elasticity to the supporter connection even after the elasticity of the supporter itself has been destroyed, and which may be readily and conveniently secured to position or released therefrom.

Further objects of the invention are to provide a device of the class stated which is simple in its construction and arrangement, strong, durable and efficient in its use, compact, positive in its action, attractive in appearance, and comparatively inexpensive to manufacture.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed without departing from the spirit of the invention.

In the drawing wherein like numerals of reference designate corresponding parts throughout the several views:

Figure 1 is a front view of my improved supporter clasp illustrating its connection with a stocking.

Figure 2 is an enlarged front view of the device, partly in cross section.

Figure 3 is a side view thereof.

Figure 4 is a bottom plan view of the device.

Referring in detail to the drawing my improved device comprises an integrally formed clamping member 1 consisting of a pair of horizontally extending, parallel disposed clamping jaws, respectively, indicated

at 2 and 3. The jaws 2 and 3 are oblong and joined, centrally of their lengths at their top edges by a vertically disposed supporting strip, which is bent together centrally of its length to provide a pair of resilient supporting arms, respectively indicated at 4 and 5.

The clamping member 1 is constructed from resilient sheet metal, and the clamping jaws 2 and 3, together with adjacent portions of respective supporting arms 4 and 5, are normally spaced from each other, as clearly shown in Figures 3 and 4. The clamping jaws 2 and 3 are formed with a slight longitudinal curvature conforming to the mean curvature of the human leg, against which they are designed to seat.

Each of the supporting arms 4 and 5 is provided with an elongated, longitudinally extending slot 6. The slots 6, in respective supporting arms 4 and 5 are disposed parallel relatively to each other except for deviation therefrom due to the normal spaced spread of the latter.

A clamping slide is mounted on the supporting arms 4 and 5, and consists of a pin 7 provided with heads 8 and 9. The pin 7 extends through the supporting arm slots 6 and the head 9 is positioned against the outer side of the inner arm 5, while the head 8 is positioned against the outer side of the outer arm 4, as clearly shown in Figure 3.

The length of the pin 7 is such that when the clamping slide is forced downwardly on the arms 4 and 5, the clamping jaws 2 and 3 will be drawn toward each other to the engaging position against the normal resilient spreading action of the resilient arms 4 and 5. When the clamping slide is shifted upwardly, the resilient action of the arms 4 and 5 will effect the positioning of the clamping jaws 2 and 3 to their normal spaced relation in the releasing position.

A gripping pad 10 is mounted on the inner concaved side of the clamping jaw 2, and a similar gripping pad 11 is mounted on the opposed convex side of the other clamping jaw 3. The gripping pads 10 and 11 are fixed in position in any suitable manner and are constructed from rubber, cork, or any other

suitable material having equivalent gripping properties. The purpose of the pads 10 and 11 is to provide a more efficient gripping engagement on the stocking A, when the top margin of the latter is secured between the 5 clamping jaws 2 and 3, as shown in Figure 1.

The clamping member 1 is suspended from a metallic spring member 12 of any suitable construction. The latter has its lower end attached to the upper joined end of the supporting arms 4 and 5. The upper end of the spring member 12 is secured to the lower end of the supporter strap 13, by means of a loop connector 14, which is attached by 15 stitching 15.

In stocking supporter devices, the straps 13 are usually constructed from elastic strap material. After prolonged use the elasticity of these straps 13 is invariably impaired or 20 entirely destroyed, whereby undue strain is imparted to the stocking itself, causing tears and runners and otherwise ruining the stocking and thereby rendering the latter unfit for further wear.

25 The embodiment of the spring member 12 in my improved device establishes a permanent and substantial elastic connection entirely eliminating the destructive effects of strains and pulls upon stockings by supporter 30 straps in which the elasticity has been impaired or destroyed. The effects of such pulling strains are further minimized by the length of the clamping jaws 2 and 3, which engage a relatively large portion of the stocking top and distributes the pulling strain over 35 a comparatively large area of the stocking.

In the construction of my improved supporter clasp, the spring member 12 is preferably enclosed in a cover sleeve 16, which is 40 open at its lower end and connected to the supported strap 13 at its upper end. This arrangement of the cover sleeve 16 will permit of the free functioning of the spring member 12 therein while enclosing the same 45 from view.

45 A flap 17 is preferably disposed at the rear side of the supporter clasp, overlapping the latter to prevent contact of the metal parts thereof with the skin of the user. The flap 50 17 has its upper end secured to the supporter strap 13, and its central portion to the inner side wall of the cover sleeve 16 at the lower end of the latter, as indicated at 18. The lower end of the flap 17 is free to allow proper 55 functioning of the supporter clasp in the manner stated.

What I claim is:

In combination, a hose supporter clasp of the character described comprising a pair of 60 integrally formed resilient supporting arms, a clamping jaw carried at the lower end of each of said arms, each of said arms being provided with a longitudinally extending slot, a clamping slide extending through said slots 65 in said arms and shiftable for drawing said

jaws toward each other, a metallic spring for suspending said arms from a supporter strap, a cover sleeve enclosing said spring, and gripping elements fixed to the opposed faces of said clamping jaws.

In testimony whereof I affix my signature. 75
THOMAS C. GRACE.
